UNITED STATES PATENT OFFICE.

PAUL VERPILLIER, OF NEWARK, NEW JERSEY.

DESIGN FOR A FINGER-RING.

SPECIFICATION forming part of Design No. 21,570, dated May 24, 1892.

Application filed April 28, 1892. Serial No. 431,061. Term of patent 3½ years.

To all whom it may concern:

Be it known that I, PAUL VERPILLIER, a citizen of the United States, residing at Newark, in the county of Essex and State of New Jersey, have invented and produced a new and original Design for a Ring, of which the following is a specification, reference being had to the accompanying drawings.

This design has for its object to provide a novel and ornamental ring, and the leading features thereof reside in a ring having arms or lugs and a cannon-shaped ornament having trunnions or supports made to rest on the arms or lugs.

This design is illustrated by the accompanying drawings, in which—

Figure 1 is a face elevation of the ring. Fig. 2 is a plan view of Fig. 1.

In the drawings the letter A indicates the ring, provided with arms or lugs B. The cannon-shaped ornament C has trunnions or supports D made to rest on the arms or lugs B.

The design provides a novel and ornamental ring which presents a distinguishing and characteristic appearance to the eye.

What I claim as new, and desire to secure by Letters Patent, is—

The design for a ring, substantially as shown and described.

In testimony whereof I have hereunto set my hand in the presence of two subscribing witnesses.

PAUL VERPILLIER.
